UNITED STATES PATENT OFFICE.

NELSON E. FRISSELL, OF GARDNER, AND WILLIAM A. MALOY, OF EAST TEMPLETON, MASSACHUSETTS, ASSIGNORS, BY MESNE ASSIGNMENTS, TO HEDSTROM-UNION COMPANY, OF GARDNER, MASSACHUSETTS, A CORPORATION OF MASSACHUSETTS.

SHAPED REED ARTICLE AND METHOD OF MAKING IT.

Application filed February 28, 1923. Serial No. 257,743.

This invention relates to the manufacture of shaped reed fabrics and has particular reference to the manufacture of reed hoods or tops for children's vehicles, as baby carriages.

The usual reed top or hood for a baby carriage or the like is composed of reed fabric which is curved in two transverse directions. The hood heretofore has usually 10 been constructed of a wooden frame having bowed transverse members and the reed fabric either has been woven upon the frame or, if woven independently of the frame, attached thereto. The wooden frame is expensive, sometimes comes apart, is heavy and clumsy, and requires skilled workmen to construct and to incorporate the reed fabric therewith.

One of the objects of the present invention 20 is the provision of a shaped reed article as a hood for a baby carriage or perambulator, which hood consists of a shaped reed fabric having binder or bow members at the edges of the fabric to hold the fabric in shape, the 25 binder or bow members constituting the frame of the article and the sole supporting and shape-retaining means for the fabric.

Another object of the invention is the provision of a shaped reed hood wherein the 30 front and rear edges of the shaped reed fabric are secured to metal bows which retain the fabric in the shape imparted to it and constitute the frame for the hood.

Another object of the invention is the 35 method of making the hood or shaped reed article above set forth.

A further object of the invention is the method of manufacturing a shaped reed article which consists in shaping the reed 40 fabric and also the frame to which the fabric is attached and progressively securing the shaped portions of the fabric and the frame together as the shaping progresses.

A yet further object of the invention is a 45 method of shaping an article as a hood for a baby carriage which consists in providing a reed fabric having a curved edge that has high and low portions and such character that when the fabric is sufficiently bent into 50 the desired shape, both the high and low portions of the curved edge will lie in a single plane which is transverse to the fabric, and securing said edge of the reed fabric permanently to a bowed supporting frame in

the aforesaid relation so as to retain the fabric permanently in the shape imparted to it. 55

A further object of the invention is generally to improve the construction of shaped reed fabrics and articles and methods of making them. 60

Fig. 1 is a side elevation of a hood for a baby carriage embodying the invention.

Fig. 2 is a plan view of Fig. 1.

Fig. 3 is a plan view of a fabric sheet prior to the shaping thereof. 65

Fig. 4 is a plan view of a machine for shaping the bows of the hood and simultaneously clamping the edges of the reed fabric therein.

Fig. 5 is a detail of Fig. 4 at the start of 70 the shaping operation.

Fig. 6 is a detailed elevation showing the position of one edge of the reed fabric in a bow prior to the shaping of the bow.

Fig. 7 is a detail of the machine of Fig. 75 1 illustrating the partly shaped bow and fabric.

Fig. 8 is a sectional detail taken along line 8—8 of Fig. 5.

Fig. 9 is a perspective detail of the fabric 80 in the bow and illustrating various positions taken by the bow and the bending thereof.

Fig. 10 is a view similar to Fig. 1, but showing the hood prior to the application of the side binder members. 85

Fig. 11 is a section through line 11—11 of Fig. 1.

Figs. 12, 13 and 14 are perspective views of the fabric at the start of the shaping, when partially shaped, and when completely 90 shaped, respectively, showing how the high and low portions of the curved edge of the fabric, when the fabric is bent into the proper shape, is caused to lie in a common plane. 95

The invention is here shown incorporated in a hood 10 adapted for use on a baby carriage or, it may be, a doll carriage. The hood is composed of a woven reed fabric body 12 and metal side bows 14 and 16, 100 which bows are or may be identical. The ends of the bows are secured to the usual hinge members 18. Side members 20 enclose the side edges of the reed fabric between the bows and are secured, as welded, 105 to the bows, above the hinge members thus to form with the bows a rigid frame structure. The bows are generally semi-circular

in form and the hood, in a longitudinal plane, is curved downwardly at both bow-ends as at *a*, Fig. 1, and has a more or less flat intermediate section *b*. The hood is 5 also transversely curved between the bows. The bow members as well as the side members 20 are formed of U-shaped, or channel, sections, see Figs. 9 and 11, and the bow-members have flattened ends 22, see Figs. 4 10 and 9, and are open intermediate the ends. The edges of the reed fabric are received within the open channels of the bow and side members and the side walls of said members are compressed into intimate engagement 15 with the fabric, thus to hold the fabric firmly and permanently therein and in the shape imparted to the fabric. The reed fabric is woven independently of the hood and is initially of generally flat shape as 20 shown in Fig. 3. The particular fabric here shown comprises the round stakes 24 and interwoven flat filler strands 26. Both the stakes and the strands are inextensible and the stakes are further apart than the 25 strands. Both the stakes and the strands are of artificial reed, that is to say, they are made of paper stock, although such need not necessarily be the case. While the filler strands 26, here shown, are flat, they can be round 30 or of any other usual or suitable shape or construction common in the art.

In the manufacture of the hood herein shown, a flat sheet of reed fabric of suitable dimensions is shaped to provide the oppositely curved front and rear edges 28, Fig. 3, which edges are adapted to lie within the front and rear bows of the completed hood. Said curved edges in general lie across the stakes 24 and the ends of the stakes terminate in said edges. The side edges 30, lying 35 between the curved edges, may be of any configuration and preferably are straight and form the side edges of the shaped hood and lie between the bows and within the side members 20. The shape of the opposed edges 28 is important. The curves of the edges, for the symmetrical hood here shown, are identical and each has a low middle portion and high end portions. The configuration 40 is such that both the low, the high and intermediate portions are caused to lie in the same plane, transversely disposed with respect to the fabric, when the fabric is shaped by applying pressures thereto in a 45 direction to flex the fabric across the edge and also in a direction to flex it forwardly and downwardly toward said edge. The bows are shaped during the fabric-shaping operation, and the fabric and bow-shaping 50 steps are effected alternately; and the fabric is secured in the bow-member coincidently with the shaping of the bow member.

The shaping operations are carried out with the assistance of the machine shown in 55 Figs. 4 and 5. Said machine comprises es-

sentially a horizontal base plate 32 provided with an upstanding anvil 34. A cam block 36 is mounted in front of and is movable toward and away from the anvil and is guided in such movement by means including the posts 38 which are carried by and upstanding above said base plate and are received loosely in slots 40 of the cam member. Said cam member is adapted to be moved towards the anvil and held releasably 75 clamped against a straight bow member therein by a cam arm 42 pivoted on a post 44 in front of said cam member. Said cam arm is adapted to bear against a projection 46 of the cam member and, when rotated in a clockwise direction, to force the cam member toward the anvil and hold it releasably in advanced position against the bow member on the anvil. A tensile spring 48 connected between said fixed post 44 and the cam member serves to withdraw the cam member from advanced position when the cam arm is free therefrom.

The rear curved face of the cam member included between the lines *c*—*c* is given a 90 generally semicircular shape which is adapted to be imparted to the bow members and to the reed fabric.

A pair of arms 50 are each pivoted to one of the posts 38 and carry on their upper 95 faces rollers 52 which are adapted to exert a pressure on a straight bow member and flex it into the shape of the cam member 36. Links 54 are pivoted to said handles and extend laterally therefrom and said links are also pivoted to other and forwardly-extended links 56 which have handle grips 58 attached thereto. Upstanding blocks 60 are swiveled on said links at the free ends thereof and have vertical slots 62 therein 100 in which flattened ends of the straight bow members are adapted to be received.

A flat spring plate 64 is extended from one block to the other and across the rollers 52 and the anvil 34 and between said cam member 36 and said rollers and anvil. The pressure of the rollers is adapted to be exerted on said spring plate and through said plate to the bow member, thus to flatten the channel of the bow member and compress its side walls upon the stakes and strands of the reed fabric. The use of said spring plate distributes the pressure of the rollers over the channel member and gives a smooth 110 contour to the bent bow member that would not be obtained without the spring plate since the roller otherwise would have a tendency to bed into the channel between the incompressible stakes of the reed fabric.

In forming the hood, the flattened ends 115 of a straight bow member 14 are inserted in the slots 62 of the swivel blocks 60 so that the middle of the channel of the bow member is opposite the anvil, as shown in Fig. 4. One of the curved edges of the fabric 120

sheet 12 is inserted in the middle of the channel so that the middle of the curved edge, or the low portion thereof, occupies the middle of the channel. The cam member 36 is then forced up against the bow member and squeezes and compresses it against the anvil and flattens the sides of the channel, in the middle thereof, upon and into permanent clamping engagement with the middle portion of the fabric sheet at the curved edge thereof, as is illustrated in Figs. 5 and 6.

In this position, the middle or low portion of the curved edge of the fabric lies within the middle of the channel while the ends or high portions of the curved edge upstand above and outside the channel. Pressure is then exerted on one side of the fabric sheet, which upstands above the side of the channel, as for instance, the left side, to flex it inwardly and forwardly toward the cam member 36 and also downwardly so that a portion of the curved edge 28 of the fabric nearest the clamped middle portion is caused to be located within the plane of bend of the bow member and disposed within the uncompressed portion of the channel thereof. The left hand arm 50 is then swung a little in a counterclockwise direction, thus to cause the roller thereof to act on and to bend the left hand side of the bow member about a portion of the cam face of the cam member and also to flatten the side walls of the channel of the bow member into permanent engagement with the inserted portions of the loose curved edge 28 of the fabric. Pressure is then again exerted on the fabric in the same general direction and manner so that a further section of the free edge of the fabric is brought down toward the plane of bend of the bow member and is caused to be located within the uncompressed portion of the channel of the bow member. The arm 50 is then again moved forwardly a suitable distance, thus to bend the bow member additionally towards its final shape and also to clamp permanently therein the loose inserted portion of the curved edge. The bending or shaping of the fabric to bring the curved edge into the channel and the shaping of the channel and the clamping of a portion of the fabric edge is carried out in successive steps until one entire side of the fabric is clamped permanently into the channel and the bow member is completely bent to the proper shape. The same series of operations is repeated on the opposite side of the fabric and channel. The handles 58 are operated at suitable times to assist in the bending of the channel into bow form.

A half completed hood with one completed bow member is then removed from the device and the same operation is car-

ried out on the other edge of the fabric so that after the bow members are applied, the hood with its bow members is completely shaped or is as shown in Fig. 10. The bow members retain the fabric in the shape imparted to it, without other restraining means, and the shaped fabric is caused to incline the ends of the bow members toward each other, so that they are caused automatically to assume their intended relative positions, as shown in Fig. 1, without necessity for forcing them into such position.

The straight side edges 30 of the fabric remain straight and lie between the bows as shown. Side members 20 of channel shape are inserted over the loose ends of the filler strands 26 at the edges 30, as shown in Fig. 11, and the side walls of said members are compressed onto the filler strands whereby to bind them securely in place. The ends of the side members 20 are preferably spot-welded electrically to the bow members 14 and 16, thus rigidly to connect them.

The above method of shaping the fabric and the bow members and simultaneously securing the fabric in the bow members can be effected by operatives inexperienced in reed manufacture. As above stated, the curve given the curved edges 28 of the fabric is important and is determined mainly by trial. The curve is such that when the fabric is completely secured in the bow members, the edge 28 of the shaped fabric occupies a plane which is the plane of the shaped bow member.

Figs. 12, 13 and 14 illustrate in some degree the manner in which both the high and low portions 12^a and 12^b, respectively, of the fabric are caused to lie in the same plane. In Fig. 12, the fabric is illustrated at the start of the shaping process, the U-shaped line 14^a illustrating the final outline of the edge. In Fig. 13, the fabric is partly shaped and sections of the edge of the fabric, between the low or middle portion and the high or end portions, have been bent forwardly and downwardly into the final plane of bend, the high end portions being yet above the final plane. In Fig. 14, all portions of the edge are shown as occupying the final plane of bend. The fabric naturally assumes the shape herein illustrated in the process of manufacture without the necessity for shifting the weave of, or shucking, the fabric, during the shaping thereof. Furthermore, since the ends of the stakes 24 of the fabric are clamped in the bow members, and the stakes are inextensible, the fabric is held against shucking during the shaping thereof and also in the completed article.

We claim:

1. The method of producing a curved reed fabric which consists in forming a piece of reed fabric with a suitably curved

edge, and bending the fabric transversely of said curved edge and in a direction to bring the ends of said edge toward each other and to cause the curved edge to lie in one plane which is transverse the body of the fabric.

2. The method of producing a curved reed fabric which consists in forming a piece of reed fabric with a suitably curved edge, 10 and bending the fabric transversely of said curved edge and in a direction to bring the ends of said edge toward each other and to cause the curved edge to lie in one plane which is transverse the body of the fabric, 15 and securing said edge permanently in the aforesaid relation.

3. The method of producing a curved reed fabric which consists in forming a piece of reed fabric with a curved edge 20 which is low in the middle and high at the ends and has such curvature that when the fabric is bent to bring the high ends suitably toward each other all portions of the curved edge will lie in one plane, bending 25 the fabric into the above condition, and securing the curved edge of the fabric to cause it to retain the shape imparted to it.

4. The method of producing a reed hood which consists in providing a piece of reed 30 fabric with opposed curved edges which are low in the middle and high at the ends, bending each curved end of the fabric separately by applying pressure to the sides of the fabric to bring the high ends of each 35 curved edge toward each other and also bending the fabric beyond the edge in a direction toward the edge to curve the fabric in two transversely related directions and to locate the high ends and low middle of 40 each curved edge in one plane, and securing each edge in the aforesaid relation so as to retain the fabric in the shape imparted to it.

5. The method of producing a reed hood 45 which consists in providing a piece of reed fabric with opposed curved edges which are low in the middle and high at the ends, bending each curved end of the fabric separately by applying pressure to the sides of the fabric to bring the high ends of each 50 curved edge toward each other and also bending the fabric beyond the edge in a direction toward the edge to curve the fabric in two transversely related directions 55 and to locate the high ends and low middle of each curved edge in one plane, securing each edge in the aforesaid relation so as to retain the fabric in the shape imparted to it by a metal binder strip applied to each 60 edge, and securing said binder strips together.

6. The method of producing a curved reed fabric which consists in providing a piece of reed fabric with a curved edge 65 which is high in one portion and low in

another portion, holding the fabric at the low portion of the curved edge, bending the fabric transversely of the curved edge into a condition wherein both the high and low places of the curved edge lie in one plane which is transverse to the bent body of the fabric, and securing said curved edge so that it and the fabric retains the shape imparted thereto.

7. The method of producing a curved reed fabric which consists in providing a piece of reed fabric with a curved edge which is high in one portion and low in another portion, holding the fabric at the low portion of the curved edge, bending the fabric transversely of and also toward the curved edge and into a condition in which the fabric is curved in two transversely related planes and in which both the high and low portions of the curved edge lie in one plane which is transverse to the curved body of the fabric, and securing said curved edge so that it and the fabric retains the shape imparted thereto.

8. The method of producing a curved reed fabric which consists in providing a piece of reed fabric with a curved edge which is high in one portion and low in another portion, securing a portion of the edge to a binder strip with other portions of the edge 90 standing away from said strip and progressively bending the fabric transversely of the edge and also toward the edge to bring other portions of the edge successively to said strip, and securing such portions to the strip, 95 and bending said strip progressively in a plane which is transverse to the body of the fabric.

9. The method of producing a curved reed fabric which consists in providing a piece 100 of reed fabric with a curved edge which is high in one portion and low in another portion, securing a portion of the edge to a binder strip with other portions of the edge 105 standing away from said strip and progressively bending the fabric transversely of the edge and also toward the edge to bring other portions of the edge successively to said strip, and securing such portions to the strip and at the same time bending the strip in a 110 plane which is transverse to the body of the fabric.

10. The method of producing a curved reed fabric with a curved edge, securing a portion of the edge to a binder strip with other portions of the edge standing above and away from the strip, bending the strip transversely of the fabric body and also bending the fabric transversely of said edge to bring the edge to the strip, and securing the edge to the strip so as to hold the edge 120 and the fabric in curved condition.

11. The method of producing a curved reed fabric which consists in providing a piece of reed fabric with a curved edge, se- 125

curing a portion of the edge to a binder strip with other portions of the edge standing above and away from the strip, and in a progressive manner bending the fabric 5 transversely of said edge to bring successive free portions of the edge to the engagement of the strip, and bending the strip transversely of the body of the fabric and securing the edge to the strip, until the strip 10 is suitably curved and the edge of the fabric is secured thereto.

12. The method of producing a curved reed article which consists in providing a piece of reed fabric with a curved edge, securing 15 a portion of the edge to a binder strip, bending the fabric and the strip in different directions and the fabric in a manner to cause its curved edge to move into the plane of bend of the strip, and securing the 20 edge to the strip so as to retain the fabric in the shape imparted to it.

13. The method of producing a reed hood which consists in providing a piece of reed fabric with a curved edge which is low in the 25 middle and high at the ends, clamping the low middle in the middle of a straight channel member with the fabric piece upstanding thereabove, bending the fabric downwardly and the side inwardly to cause both 30 the high and low portions of the curved edge to lie in the plane of bend of the channel member, bending the channel member in a horizontal plane and clamping the channel member upon the bent curved edge of the 35 fabric.

14. The method of producing a curved reed fabric which consists in providing a piece of reed fabric having inextensible stakes and filler strands with a curved edge

in which the stakes are terminated, bending 40 the fabric across the stakes and also across the filler strands until the ends of the stakes in the curved edge are in one plane, and securing a binder strip to said edge to hold the fabric in the shape imparted to it. 45

15. A reed hood consisting of a reed fabric which is curved in two transversely-related planes, bow-members secured to the opposite ends of the curved fabric, the bow-members retaining the fabric in the shape 50 imparted to it, the fabric between the bow members being self-supporting, and means securing the ends of the bow members on the same side of the fabric together.

16. A reed hood consisting of a reed fabric 55 which is curved in two transversely-related planes, bow-members secured to the opposite ends of the curved fabric, the bow-members retaining the fabric in the shape imparted to it, the fabric between the bow 60 members being self-supporting, and side members extended between the bow members and secured to the free edges of the fabric between the bow members.

17. A reed hood consisting of a reed fabric which is curved in two transversely-related planes, bow-members of channel formation secured to the opposite ends of and enclosing the end-edges of the fabric, and side channel members extended between and 70 rigidly fixed to said bow members and enclosing and secured to the edges of the fabric at the sides thereof between said bow members.

In testimony whereof, we have signed our 75 names to this specification.

NELSON E. FRISSELL.
WILLIAM A. MALOY.
